DESIGN FOR A CABINET FOR GREASING
EQUIPMENT OR THE LIKE

Harold Van Doren and Walker Johnson, Toledo,
Ohio, assignors to The Aro Equipment Corpora-
tion, Bryan, Ohio, a corporation of Ohio

Application March 20, 1939, Serial No. 83,713

Term of patent 7 years

To all whom it may concern:

Be it known that we, Harold Van Doren and Walker Johnson, citizens of the United States, and residents of Toledo, in the county of Lucas and State of Ohio, have invented a new, original, and ornamental Design for a Cabinet for Greasing Equipment or the like, of which the following is a specification, reference being had to the accompanying drawing, forming part thereof.

Figure 1 is a perspective view of a cabinet for greasing equipment or the like showing our new design, the reverse side thereof being substan-

tially similar with respect to the solid line showing; and

Figure 2 is a plan view thereof.

The dominant features of our design reside in the parts shown by solid lines on the drawing.

We claim:

The ornamental design for a cabinet for greasing equipment or the like, substantially as shown and described.

WALKER JOHNSON.
HAROLD VAN DOREN.
